10 Claims. (Cl. 211—13)

ABSTRACT OF THE DISCLOSURE

A rigid open wire frame having folded cardboard enclosures removably housing the upper and lower ends of the frame. The lower enclosure has an upper surface for supporting a doll or a seat for a doll and holding means on the frame hold the doll in position on the surface or seat. The upper enclosure has a front face on which an identifying label is removably mounted.

The present invention relates to an apparatus for displaying articles, such as toy figures or dolls, and, more particularly, pertains to a display apparatus comprising separable parts which can be readily interchanged to display one or more articles of various sizes and configurations.

It is an object of the present invention to provide a display apparatus which is economical to manufacture, readily assembled and disassembled, simple in construction, and which comprises parts that are readily interchangeable to enable it to be used for displaying various types of articles.

Another object is the provision of a new and improved apparatus for displaying one or more articles of various configurations and sizes, and in various positions.

A further object is to provide a display apparatus which is especially adapted for supporting one or more miniature or toy figures, such as dolls, of various configurations and sizes, and in various positions, such as a standing, sitting or walking position.

Still another object is the provision of a display apparatus comprising parts which may be readily assembled into a substantially rigid structure which is self-supporting on a support surface, or which may be supported in an elevated position on a suitable support, such as a wall or frame or the like.

A still further object is the provision of a new and improved display apparatus which is streamlined and attractive in appearance and which is so constructed as to focus attention on the one or more articles being displayed thereon.

An additional object is to provide a new and improved display apparatus which incorporates a marquee for the identification of one or more articles being displayed thereon, the marquee being adapted to removably support identifying labels having names or characters thereon which correspond to the article or articles being displayed on the stand.

According to the present invention, the display apparatus comprises an upstanding, self-supporting frame comprising a series of horizontal and vertical wire elements which may be removably or permanently, rigidly secured together. A pair of enclosures, preferably formed of a material such as cardboard which can be set up from a relatively flat, foldable blank, are removably secured over the ends of the wire frame. The enclosure at the upper end is provided with a marquee which is adapted to removably receive identifying labels having names or other characters thereon for identifying articles to be displayed on the apparatus. The cardboard enclosure at the lower

end of the wire frame serves as a base for supporting articles to be displayed on the apparatus, and also is provided with one or more slots or openings in the upper surface thereof for removably receiving one or more resilient channel members that are adapted to slidably receive various types of removable spring elements having holding arms. The holding arms may be of any suitable number, size and configuration for the supporting of articles, such as dolls, of various sizes and configurations.

As an alternate arrangement, a seat or support member, which can be set up from a relatively flat, foldable blank, preferably of a cardboard material, may be removably retained on the lower enclosure by inserting a tab on the seat member through a corresponding slot in the upper surface of the enclosure, to thereby function to support one or more dolls in a seated position or in an elevated standing position.

The present invention, both as to its organization and manner of operation, together with further objects and advantages thereof, may best be understood by reference to the following description, taken in connection with the accompanying drawings in which like reference characters refer to like elements in the several views.

In the drawings:

FIGURE 1 is a perspective view of a display apparatus constructed in accordance with the principles of the present invention;

FIGURE 2 is a plan view of the upper end of the display apparatus shown in FIGURE 1, taken substantially along line 2—2 of FIGURE 1;

FIGURE 3 is an enlarged perspective view of the rear upper portion of the display apparatus shown in FIGURE 1, showing the manner in which the upper enclosure is mountable on the upper portion of the supporting frame of the apparatus, and showing the removability of an identifying label from the marquee portion of the upper enclosure;

FIGURE 4 is a perspective view of a cut, scored and assembled blank from which the upper enclosure for the display apparatus may be assembled;

FIGURE 5 is an enlarged sectional view taken substantially along line 5—5 of FIGURE 1;

FIGURE 6 is a perspective view of a cut, scored and assembled blank from which the seat member shown in FIGURES 1 and 5 may be assembled;

FIGURE 7 is an exploded perspective view of the elements of the wire supporting frame of the instant display apparatus, showing one form of attachment for the assembling of the horizontal and vertical wire elements;

FIGURE 8 is an enlarged, fragmentary exploded view in perspective, showing an alternate form of removable attachment for the wire elements of the supporting frame of the instant display apparatus;

FIGURE 9 is a perspective view of an alternate form of resilient holding member for retaining an article, such as a toy figure or doll, on the instant display apparatus;

FIGURE 10 is a view similar to FIGURE 5, showing the use of the alternate form of resilient holding member, illustrated in FIGURE 9, for retaining a doll in a seated position on the seat member of the instant display apparatus; and

FIGURE 11 is a view similar to FIGURE 10, showing the use of the alternate form of resilient holding member, illustrated in FIGURE 9, for retaining a doll in a standing position on the lower or base enclosure of the instant display apparatus.

As a preferred or exemplary embodiment of the present invention, FIGURE 1 illustrates a display apparatus 20 generally comprising an upstanding wire frame 22 having an enclosure 24, formed of a suitable flexible and foldable material such as cardboard, remov-

ably mounted on the upper end thereof, and a similar enclosure 26 removably mounted on the lower end thereof. An upstanding support or seat member 28 is removably mounted on the bottom enclosure 26 and is provided with a relatively flat upper support panel 30 through which a portion of an article supporting frame 32 extends for removable mounting on the bottom enclosure 26, in a manner to be described hereinafter. The article supporting frame 32 is adapted to retain one or more articles in various positions on both the upper panel 30 of the support member 28 and/or on the upper surface of the bottom enclosure 26, as will be more clearly understood from the description hereinafter.

Referring to FIGURE 7, the upstanding wire frame 22 comprises upper and lower, substantially horizontally extending end elements 34 and 36, respectively, each of which comprises a rear section 38 and a pair of forwardly diverging side sections 40. The rear section 38 of the upper end element 34 has an upstanding, apertured bracket 42 secured thereto in any suitable manner for the purpose of enabling the frame 22 to be hung from a support, such as a partition or wall (not shown). The rear section 38 of the lower end element 36 comprises an upstanding, generally U-shaped wire support 44 which is adapted to slidably receive an elongated channel member 46 for a purpose to be described hereinafter. The wire support 44 is rigidly secured to the rear section 38 of the lower end element 36 in any suitable or conventional, removable or permanent manner.

A pair of generally upstanding, rectangular side frame portions 48 and 50 are secured to the diverging sections 40 of both the upper and lower end elements 34 and 36, respectively. Each of the side frame portions 48 and 50 comprises vertically extending, parallel sections 52, which are connected by horizontally extending, parallel sections 54 (see FIGURE 7). While the upstanding frame sections 52 are disclosed as unitary wire elements in the drawings, it is noted that these sections should be formed of telescoping members (not shown) which are in frictional engagement and are adapted to be maintained in various relative positions of adjustment, to thereby enable the height of the frame portions 48 and 50, and that of the frame 22, to be selectively varied.

The upstanding sections 52 of the side frame portions 48 and 50 may be secured to the diverging sections 40 of the end elements 34 and 36 in any suitable manner. For example, FIGURE 7 illustrates the use of resilient spring clips 56 which are secured to the upstanding sections 52 adjacent their ends and are adapted to be snap-fitted over the diverging sections 40 of the end elements 34 and 36. The use of these resilient spring clips 56 enables the frame portions 34, 36, 48 and 50 to be substantially rigidly secured together, and to be easily disassembled in such a manner that they can be stored in a minimum of space. Alternatively, the spring clips 56 could be mounted on the diverging sections 40 of the end elements 34 and 36, rather than on the side frames 48 and 50.

As shown in FIGURE 8, instead of the spring clips 56, the upstanding sections 52 could be provided with pins 58 that are slidably receivable in apertures 60 of the diverging sections 40 of the end elements 34 and 36, for the purpose of removably securing the side frame portions 48 and 50 to the end elements 34 and 36. It is to be understood, of course, that various other means may be utilized for removably or permanently securing the side frame portions 48 and 50 to the end elements 34 and 36 of the frame 22, without departing from the spirit or scope of the instant invention. For example, if the removability of these elements is not desired, the upstanding sections 52 could be soldered or otherwise permanently rigidly secured to the diverging sections 40 of the end elements 34 and 36.

Referring to FIGURES 2, 3 and 4, the upper enclosure 24 comprises a front panel 62 which is adhesive-

ly or otherwise secured in any suitable manner to a flap 64 of a top panel 66 which, in turn, is connected to a rear panel 68 having a folded flap 70 that is adhesively or otherwise secured to a bottom panel 72 (see FIGURES 3 and 4). The bottom panel 72 is connected by a pair of diagonal fold lines 74 and 76 to a pair of side panels 78 and 80, respectively. Each of the side panels 78 and 80 has a foldable flap 82 with an outwardly extending foldable tab 84 having a pair of foldable side portions 86. As partially seen in FIGURE 4, it will be readily understood that the upper enclosure 24 may be formed and stored as a relatively flat blank having the side panels 78 and 80 extending substantially laterally outwardly from the bottom panel 72, and having the top panel 66 and the front panel 62 disposed adjacent to and lying over and under the bottom panel 72, respectively.

In the assembling of the enclosure 24 over the upper end of the frame 22, as illustrated in FIGURES 2 and 3, the front and rear panels 62 and 68 of the enclosure are folded upwardly to assume the generally parallel, vertically extending positions shown in FIGURE 3. Thereafter, the enclosure 24 is positioned adjacent the upper ends of the side frame portions 48 and 50, and the upper end element 34 of the frame 22. In this position, the bottom panel 72 of the enclosure 24 underlies the end element 34, with the side panels 78 and 80 extending beneath the diverging sections 40 of the end element 34 and between the vertical sections 52 of the side frame portions 48 and 50, respectively. The side panels 78 and 80 are then folded upwardly along the fold lines 74 and 76, respectively, into a position wherein they engage and are substantially parallel to the planes of the side frame portions 48 and 50, respectively, as shown by the arrows in FIGURE 3. The flaps 82 of each of the side panels 78 and 80 are then folded over the upper horizontal section 54 of each of the side frame portions 48 and 50, respectively, to a position wherein the tab 84 is in substantial alignment with an opening 87 in the upper panel 66, the opening 87 being of substantially the same size and configuration as the tab 84. The foldable side portions 86 of each tab 84 are then inserted within the adjacent opening 87 in the top panel 66 for the purpose of retaining the upper enclosure 24 in an assembled position on the upper end of the frame 22 (see FIGURES 2 and 3). A pair of generally circular finger apertures 89 are provided in the top panel 66 adjacent to the openings 87 for the purpose of facilitating the insertion of the tab portions 86 within the openings 87.

As shown in FIGURES 1 through 3, the front panel 62 of the upper enclosure 24 is provided with a pair of spaced, generally U-shaped slits 88 on the upper portion thereof, which are adapted to slidably and frictionally receive tabs 90 on a label member 92 for removably retaining the latter on the front panel 62. It will thus be readily seen that the front panel of the upper enclosure 24 serves as a marquee for displaying label members having various forms of characterizing indicia or designs thereon for identifying different articles to be displayed on the instant apparatus.

The bottom enclosure 26 for the frame 22 is not disclosed in detail herein because it is of substantially identical construction to that of the upper enclosure 24 hereinbefore described. The lower enclosure 26, however, is assembled on the lower end of the frame 22 in a position opposite to that of the upper enclosure 24, i.e., the upper panel 94 of the lower enclosure 96 corresponds to the lower panel 72 of the upper enclosure 24, and the front panel 96 of the lower enclosure 26 extends downwardly rather than extending upwardly in the manner of the front panel 62 of the upper enclosure 24. The side panels 98 of the lower enclosure 26, therefore, extend downwardly from the upper panel 94 and have flaps and tabs which are folded underneath the lower end element 36 and the side frame portions 48 and 50, to lock the lower enclosure in an assembled position

on the frame 22 in a manner substantially the same as that in which the upper enclosure 24 is assembled on the frame (see FIGURE 5).

Referring to FIGURE 6, the seat or support member 28 comprises a front panel 100 to which the upper support panel 30 is hingedly attached, a pair of side panels 102 and 104, and a rear panel 106, all of which are integrally connected by fold or hinge lines of a blank formed of a suitable flexible and foldable material, such as cardboard or the like. The front panel 100 is provided with a depending tab 108 which is adapted to be inserted through a slot 110 in the upper panel 94 of the lower enclosure member 26, for the purpose of retaining the seat member 28 thereon (see FIGURES 1 and 5). The upper panel 30 is provided with a pair of rearwardly opening notches 112 for the purpose of retainably engaging the adjacent pair of upstanding frame sections 52 (see FIGURE 1), and with a generally laterally extending slot 114 which is adapted to be vertically aligned with a complementary slot 116 in a foldable tab 118 on the bottom of the rear panel 106, when the upper panel 30 and the tab 118 on the rear panel 106 are folded into substantially horizontal, parallel positions, as shown in FIGURES 1 and 5.

The seat member 28 may be assembled or set-up from the blank shown in FIGURE 6 and mounted on the upper panel 94 of the lower enclosure 26 by folding the front and rear panels 100, 106, and the side panels 102, 104 into a generally rectangular form, and by folding the upper panel 30 and the tab 118 of the rear panel 106 into substantially horizontal, parallel positions. The set-up seat member 28 then is placed on the upper panel 94 of the lower enclosure 26 in a position wherein the depending tab 108 of the front panel 100 extends through the slot 110 in the upper panel 94 of the lower enclosure 26. In this position, the slot 116 in the horizontally extending tab 118 on the rear panel 106 receives the upstanding, generally U-shaped support 44 secured to the lower end element 36 of the frame 22, the supporting element 44 extending upwardly through a slot 120 in the upper panel 94 of the lower enclosure 26, which is disposed beneath and vertically aligned with the slot 116 in the tab 118 (see FIGURES 1 and 5). The bottom portion of the seat member 28, therefore, is removably anchored on the upper panel 94 of the lower enclosure 26, and the upper portion thereof is maintained in position by the engagement of the recessed portions 112 of the upper panel 30 with the adjacent upstanding frame sections 52.

The elongated channel member 46 is receivable within the slot 114 in the upper panel 30 of the support member 28, and the lower end thereof is adapted to frictionally receive the upstanding, generally U-shaped support 44 on the lower frame element 36 for the purpose of supporting the channel member 46 on the frame 22 (see FIGURES 5 and 7). The upper end of the channel member 46 is adapted to slidably and frictionally receive a pair of depending legs 122 of the article supporting frame 32, which terminate at their lower ends in an integral, U-shaped connecting portion 124 (see FIGURE 1). Secured to the upper ends of the legs 122 in any suitable manner, is a wire element 126 having a rear section 128 and outwardly diverging side sections 130, which are substantially parallel to the rear and side sections of the upper and lower end elements 34 and 36 of the frame 22. On the ends of each of the side sections 130 of the article supporting frame 32, there are secured generally U-shaped, resilient retaining members 132 which are adapted to engage and retain articles, such as toy figures or dolls, to be displayed on the instant apparatus 20 (see FIGURES 1 and 5). The ends of the side sections 130 are further provided with depending wire elements 134 for engagement with the rear portion of a toy figure or doll being engaged by

the adjacent resilient retaining member 132. The article supporting frame 32 also comprises an upstanding wire element 136 which is secured to the rear section 128 and terminates in a third generally U-shaped resilient retaining member 138, which is engageable with an article to be supported on the instant apparatus. The wire element 136 also supports a depending wire element 140 which is adapted to serve a function similar to the depending elements 134 on the ends of the side sections 130 of the frame 32.

It will be readily seen that the display apparatus shown in FIGURES 1 and 5 can be used to support and retain three articles, such as toy figures or dolls, by placing two of them on the upper panel 94 of the lower enclosure 26 and engaging them with the U-shaped, resilient retaining members 132, and by placing the third figure or doll on the upper panel 30 of the seat member 28 and maintaining it thereon by engaging it with the U-shaped retaining member 138 on the upstanding wire element 136 of the frame 32 (see FIGURE 5).

If the seat member 28 were to be removed from the apparatus shown in FIGURES 1 and 5, a figure could be supported in a hanging, elevated position on the U-shaped retaining member 138, rather than in a standing position on the upper panel 30 of the support member 28. Further, it will be readily understood that the article supporting frame 32 may be constructed in any other suitable manner and with any suitable number of article retaining members of various sizes and configurations, depending on the type of articles to be displayed, without departing from the scope of the instant invention.

FIGURES 9 through 11 are directed to a modified article supporting member 200 which can be utilized with the instant display apparatus as a substitute for the article supporting frame 32 shown in FIGURES 1 and 5. The modified supporting member 200 comprises a pair of legs 202 which are connected at their lower ends by a U-shaped section 204, and which diverge upwardly and terminate in laterally extending, arcuate and resilient arms 206 having protective end covers or coatings 208 (see FIGURE 9). As shown in FIGURE 10, the legs 202 of the modified article supporting member 200 are slidably receivable within the upstanding channel member 46 of the instant display apparatus 20 for the purpose of supporting a toy figure or doll in a seated position on the upper panel 30 of the support member 28, by the engagement of the resilient retaining arms 206 with opposite sides of a portion of the figure.

If it is desired to display a toy figure or doll in a standing position on the instant display apparatus, the seat member 28 may be removed from the lower enclosure 26, and the figure may be placed in a standing position on the upper panel 94 of the bottom enclosure and retained thereon by engaging it with the resilient retaining arms 206 of the modified retaining member 200, as shown in FIGURE 11.

The upwardly diverging configuration of the resilient legs 202 of the modified retaining member 200 enables it to be mounted within the channel member 46 in various positions of vertical adjustment, owing to the resilient frictional engagement between the legs 202 and the channel member 46. This arrangement, therefore, enables articles or figures of various sizes and shapes to be displayed on the instant display apparatus 20, and to be conveniently engaged by the resilient retaining arms 206 of the modified retaining member 200.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the forms hereinbefore described being merely preferred embodiments thereof.

What is claimed is:

1. Article display apparatus, comprising:
an upstanding rigid open frame having spaced upstanding members,
first foldable sheet means separate from said frame and enclosing only the lower end of said frame and being removably mounted thereon, said first foldable means having an upper horizontal surface adapted to support an article thereon, and
means removably mounted on said frame for retaining an article in a predetermined position on said surface.
2. The apparatus of claim 1, further comprising second foldable means enclosing the upper end of said frame and being removably mounted thereon, said second foldable means having an upright front surface and removable means thereon for identifying an article supported on said first foldable means.
3. The apparatus of claim 1 wherein said first foldable means comprises a unitary sheet member having a plurality of foldable panels and flaps movably connected in predetermined assembled relation wherein they enclose said lower frame end, one of said panels being an upper panel disposed in a substantially horizontal plane and defining said upper surface for support of an article thereon.
4. The apparatus of claim 3 wherein said upstanding frame comprises a plurality of spaced, upstanding wire elements, first horizontally extending wire elements secured to said upstanding elements adjacent the lower ends thereof, and second horizontally extending elements secured to said upstanding elements adjacent the upper ends thereof, said panels and flaps of said foldable member being folded over and mounted on said first horizontally extending wire elements.
5. The apparatus of claim 3 wherein said upper panel of said foldable member is provided with a slot therein, and said frame includes support means extending upwardly through said slot and removably supporting said retaining means on said frame.
6. The apparatus of claim 5 wherein said retaining means comprises a pair of flexible and resilient arms for engaging an article supported on said upper panel of said foldable member.
7. The apparatus of claim 3 wherein a seat member is removably mounted on said upper panel of said foldable member, said seat member having an upper supporting surface for supporting an article in raised relation to said foldable member.

8. Article display apparatus, comprising:
a frame having a plurality of spaced, upwardly extending wire elements connected by first substantially horizontally extending wire elements adjacent the lower ends thereof and second substantially horizontally extending wire elements adjacent the upper ends thereof,
first foldable means enclosing the lower end of said frame and comprising a plurality of foldable panels and flaps extending over said first substantially horizontally extending wire elements and removably connected in assembled relation thereon, one of said panels being an upper panel disposed in a substantially horizontal plane for support of an article thereon,
support means on said frame extending upwardly from said upper panel of said first foldable means, and
resilient means removably mounted on said support means for retaining an article in a predetermined position on said upper panel of said first foldable means.
9. The apparatus of claim 8 wherein said upper panel of said first foldable means comprises a slot therein, said support means comprises a channel member extending upwardly through said slot, and said resilient retaining means comprises a depending supporting portion slidably mounted within said channel member.
10. The apparatus of claim 8, further comprising second foldable means enclosing the upper end of said frame and comprising a plurality of foldable panels and flaps extending over said second substantially horizontally extending wire elements and removably connected in assembled relation thereon, one of said panels being a front panel disposed in a substantially vertical plane and adapted to removably support a marquee thereon for the purpose of identifying an article supported on said upper panel of said first foldable means.
